Primary Examiner — T Chase Nelson*Assistant Examiner* — Jonathan J. Han(74) *Attorney, Agent, or Firm* — Novick, Kim & Lee, PLLC; Allen Xue; Hyun Woo Shin(57) **CLAIM**

I claim the ornamental design for an electronic sight, as shown and described.

DESCRIPTION

FIG. 1 is a top, rear, right side perspective view of an electronic sight showing my new design;

FIG. 2 is a front, bottom, left side perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken lines in the drawings show portions of the electronic sight which form no part of the claimed design.
